UNITED STATES PATENT OFFICE.

ALOYSIUS JOSEPH UNIACK, OF LOS ANGELES, CALIFORNIA.

FLAT-FOLD BINDING RING.

Application filed June 28, 1923, Serial No. 648,365.

To all whom it may concern:

Be it known that I, ALOYSIUS JOSEPH UNIACK, a citizen of the United States, and a resident of Los Angeles, in the county of 5 Los Angeles and State of California, have invented new and useful Improvements in Flat-Fold Binding Rings, of which the following is a specification.

This invention relates to binding loops or 10 rings for the flat-fold binding of bank checks and the like, and pertains more particularly to permanent fastening means whereby the checks may be permanently secured to a cardboard backing or the like, 15 and still be capable of being easily turned over to lie flat upon the backing.

The invention has for its principal object 20 the provision of means for enabling the manufacturer or binder to quickly and easily bind a plurality of loose leaves in permanent arrangement and in conformance with the requisites of flat-fold binding.

Usually checks, loose leaves and the like, bound in this manner, are held by staples 25 or the like which are riveted at their ends to a backing. To apply such staples, a special machine is required and the stationery is in danger of being soiled or mutilated while the operation of applying the staples is in 30 progress.

It is therefore another object of the invention to provide binding loops which may first be applied to a stack of loose leaves so 35 that this stack of loose leaves, with the loops applied, may then be expediently attached to a backing without the aid of special machines.

Still another object of the invention is to 40 provide a device of the above character which may be applied to a backing by the use of an ordinary hammer or paper fastening device, such as is employed for attaching a plurality of sheets of paper together.

A further object of the invention is to 45 provide a device of the above character which will not tend to tear the leaves or abraid them, and which when applied to a backing will not be inclined to mar a desk or surface with which they may come in 50 contact.

Still other objects and advantages will appear hereinafter and will be better understood by virtue of their occurrence.

I have illustrated by the accompanying 55 drawings a preferred embodiment of my invention and a modification thereof.

In the said drawings;

Figure 1 is a view mainly in vertical section of said embodiment.

Figure 2 is a view in side elevation thereof 60 illustrating the manner in which it is applied to a stack of checks in the first stage of the process of binding.

Figure 3 is a plan view of a backing to 65 which a plurality of checks are bound in conformance with the invention.

Figure 4 is a view mainly in vertical section of a modified form of the invention.

Figure 5 is a plan view thereof.

More specifically, in carrying out my invention I provide a binding ring 1, which in 70 the form of the invention shown in Figs. 1, 2 and 3, comprises essentially a ring element 7 and a foot 6. The ring may be of any suitable form, but is illustrated as having an 75 arcuate portion 8, and vertically rising portions 9 and 10 respectively, intersecting the arcuate portion. The lower end of portion 9 is provided with a shoulder 11, and a conical end 12 immediately below said shoulder. 80 This conical end passes through a corresponding hole 13 in the foot 6, and is peened over so that while the ring and foot are held together, said ring is capable of being 85 swung outwardly relative to said foot so that when necessary the ring may be disposed so that the foot will be easily accessible without interference from the ring, and vice versa.

The opposed end 14 of the ring, or rather 90 the end of portion 10, is of such length that it will abut foot 6 when moved into the position shown in Figs. 1 and 3. An end 15 of the foot projects beyond end 14 and is provided with an eyelet hole 16, while another 95 eyelet hole 17 is located in the foot on the other side of end 14.

In Fig. 3, a pair of binding rings above described are shown as applied to a stack 100 of loose leaves 18, which are drilled as at 19. By the use of eyelets 20 the foot of each binding ring is secured to a cardboard backing 21. Each of the loose leaves consists of a plurality of check blanks 22 and stubs 23, separated by perforations 24. When all of 105 the checks are detached, the stubs remain in a group fixed to the backing by the binding rings. Obviously, these stubs may be turned over into the position shown in Fig. 3. The checks, of course, lie upon backing 21, normally, but in Fig. 3 they are shown in reversed position to illustrate the position in 110

which they are placed during the act of binding the leaves to the backing.

In the application of the device illustrated, a ring is opened into the position shown in Fig. 2. The stack of checks 18 are held with the writing surface uppermost, and the end 14 of the ring element is inserted in the drilled holes 19. Foot 6 is then swung over to abut end 14. Similarly the other binding ring is applied. Now the assembly of the rings and leaves is inverted and laid upon the backing as, and in the position shown in Fig. 3, whereupon each foot is secured to the backing by the eyelets, and the operation may be accomplished with any of the usual portable manual devices (not shown) which are used for cinching paper-fastening eyelets.

It will be seen that during the operation of cinching the eyelets, each ring element may be swung to one side as indicated in dotted lines. This is a great advantage, inasmuch as when so positioned the rings will not offer interference to the device employed for cinching the eyelets, and the binder may work quickly and accurately. When the group of leaves as a whole are turned over to lie upon backing 21, the margins of the holes provided in the checks preclude movement of the ring elements in any direction, inasmuch as end 14 of each abuts foot 6. It will be seen that with this form of foot shown, each foot assumes an angular position in order that the ring elements may parallel the median line of the backing. Therefore the foot of each ring should converge, or diverge, relative to one another. With the end 14 of the ring element extending below the upper surface of the foot, it is impossible for leaves to become disengaged from either binding ring, and it is not essential that said end be accurately positioned to contact with the backing, or to penetrate it.

In the form of the invention shown in Figs. 4 and 5. I provide a foot 27 and a loop 28, the latter being secured to the former the same as in the first described form of the invention. Foot 27, is preferably made of a spring metal, such as spring brass, or steel. In the foot I provide two apertures, 29 and 30. Aperture 29 is positioned so that the free end 31, of the foot will align with it when the said loop is disposed parallelly with the foot, as illustrated. The foot is secured to a backing 32, or the like, by eyelets 33.

It will be apparent now that all of the foot located between the attached end of the loop and the first aperture is free to bend slightly, and by virtue of the material used, will always return to straight position when allowed to do so.

In the application and operation of this form of the invention the feet are attached

to the backing and to the leaves in substantially the manner described for the preferred form of the invention. The loops can be swung out of normal position when the eyelets are being installed. In this form of the invention the foot of each binding ring is disposed to parallel the sides of the backing to which they are secured, and are not obliquely disposed. It will be apparent that the lower free end of the loop may be raised to clear the foot and swing around until it is in alignment with aperture 29. Upon releasing the loop the said end will be forced into the aperture by the action of the foot returning to normal position.

It will be apparent now that I have provided a simple and efficient binding ring which may be opened to be attached to a stack of leaves or the like, and which upon being closed may be readily attached to a backing to hold the leaves in permanently bound arrangement with the backing, while permitting of flat opening of said leaves.

While I have shown and described a specific construction and arrangement of parts for two forms of my invention, I do not limit myself to these two forms, nor to any specific construction and arrangement of parts, and I may employ any construction and arrangement of parts as I desire or as occasion requires, without enlarging the scope of my invention, within the appended claims.

I claim;

1. In a device of the character described, a foot capable of attachment to a backing, and a substantially U shape element having one end pivotally connected to said foot so that the other end may be moved to describe an arc around the pivot point on the plane of the foot; the free end of said element extending normally below the plane of the upper surface of the foot, and the foot extending beyond the free end of the element.

2. In a device of the character described, a foot capable of attachment to a backing, and a substantially U shape element having one end pivotally connected to said foot so that the other end may be moved to describe an arc around the pivot point on the plane of the foot; the free end of said element extending normally below the plane of the upper surface of the foot, and the foot extending beyond the free end of the element; the foot being of material of spring-like characteristic and being provided with an aperture disposed in the path of travel of the free end of the element; said element being pivoted to said foot in such manner that the free end cannot be raised vertically to enter or be removed from said aperture without bending the foot.

3. In combination with a backing and a plurality of sheets having aligned perfora-

- tions, sheet fastening means including a foot secured to the backing and provided with an aperture, a hollow tubular rivet passed through the aperture to secure the foot to the backing, a substantially U shape member extending through the aligned perforations and having one end pivoted to said foot so that the other end may describe an arc in the plane of the foot; the said movable end of the member being inserted in said hollow rivet.
4. In combination with a backing and a plurality of loose leaves, a pair of binding devices, each comprising a foot attached to the backing and a substantially U-shape element engaging said leaves and being vertically disposed with regard to said foot, and having one end revolvably mounted on said foot while the free end projects below the upper margin of said foot for the purpose set forth; said feet being obliquely disposed with regard to each other and converging or diverging toward or away from each other, and the said U-shape elements being parallelly disposed with regard to each other, whereby revoluble movement of said elements is precluded.
5. In combination with a backing and a plurality of sheets having aligned perforations, sheet fastening means including a foot secured to the backing and provided with an aperture, a hollow tubular rivet passed through the aperture to secure the foot to the backing, a substantially U shape member extending through the aligned perforations and having one end pivoted to said foot so that the other end may describe an arc in the plane of the foot; the said movable end of the member being inserted in said hollow rivet, the foot being of spring-like characteristic so that the free end of the said member may be raised out of the tubular rivet, and the foot being provided with other means forwardly of the rivet for additionally holding it to the backing.

A. JOSEPH UNIACK.
